ARTICULATED RAMP STRUCTURE FOR
MINE CARS

Jean Binaut, Lewarde (Nord), France, assignor
to Houillères du Bassin du Nord et du Pas de
Calais, Douai (Nord), France, a corporation of
France

Application October 17, 1949, Serial No. 121,716
In France November 4, 1948

6 Claims. (Cl. 238—10)

1

This invention generally relates to an improved articulated structure adapted to be superimposed over a haulage track to provide a ramp or inclined plane and more specifically to such an improved articulated ramp structure adapted for use in enabling cars such as mine cars or trucks to accede to, and depart from, a tipple or tumbler device arranged on the haulage track.

Wherever it is necessary to bring such cars onto a tipple located on the car-track, the need arises of providing an inclined plane to allow the cars to climb up to, and run down from the tipple. In the case of a straight track section, this is no problem and many satisfactory solutions have long since been proposed. Where however a curved section of the track is concerned, it is quite a different matter, and up-to-date the only successful solution, so far as I am aware, comprises the use of a ramp having a fixed curvature corresponding with that of the track section with which it is to be used.

In mine workings wherein the conditions change continually from place to place, as for instance in the head- and foot-levels of work-panels cut in tortuous seams of the kind encountered in a great many mining fields all over the world, employment of such fixed-curvature ramps will entail the necessity of providing a great many different ramps having different radii of curvature varying as from 3.50 meters to about 25 meters, for the goat stowing operations. Also, where a straight ramp is used in connection with a large-radius curve, great difficulty is encountered in bringing the cars up to the tipple.

It will of course be understood that anything that may be said, throughout this specification, about bringing the loaded cars up to the tipple, also applies, mutatis mutandis, to the discharge of the emptied cars from the tipple.

It is a general object of the present invention to provide an improved ramp structure for the purpose described which obviates the above-mentioned difficulties.

Another object is to provide an improved articulated ramp structure to which any desired radius of curvature may be imparted, in a range of from about 3.50 meters to infinity (straight track section) according to the particular re-

2

quirements of the location in which it is to be installed.

A further object is to provide such an articulated variable-curvature ramp structure, adapted to be superimposed over a section of a haulage track, which is comparatively easy and cheap to manufacture and which may be quickly and readily moved from one track section to another and there have its curvature readjusted to new local conditions.

Further objects and advantages of the invention will appear as the description proceeds.

According to this invention, this articulated ramp structure comprises a number of similar units, each forming a deformable parallel linkage system, with means at each point of pivotal connection, between the members of said linkage units adapted to fit over and engage the rails, so as to provide parallel polygonal contours overlying the rails of the track. Each said linkage unit preferably comprises a pair of parallel iron sections, provided, at the opposite ends thereof, at which the iron section is pivoted to an adjacent iron section, with a foot-plate, of circular form, mounted for rotation in its plane within a support adapted to rest on the related rail, the foot-plates of the respective iron sections of any two adjacent units being mounted in a common support. At each point of pivotal connection between adjacent units, the supports are interconnected with a bracing cross-bar, which is pivoted to said supports and which is automatically self-adjustable in length in response to the particular value of the radius of curvature which the ramp assembly has to assume at the point under consideration, or the relative degree of angling between the units at that point.

Preferably, where an articulated ramp structure designed to permit access to and from a car-tipple device is concerned, the free end of each iron section of that end linkage unit which is to connect with the tipple also comprises a circular foot-plate mounted for rotation in a support smaller in length than the other supports of the assembly, and the supports of both said end iron sections are interconnected with a cross-member, of fixed length, secured to the frame of the tipple. The free ends of both end iron sections, at the opposite end of the ramp structure at which the cars enter, or leave, the ramp, are interconnected

with a cross-member automatically self-adjustable in length and pivoted at its ends to said ends of the iron sections.

The accompanying drawings illustrate, by way of example and not of limitation, one embodiment of an articulated ramp structure according to the invention, as designed for use in connection with a tipple.

Figures 1 and 2 are respective views in side elevation and in plan of the articulated ramp.

Figures 3, 4, 5 and 6 are respective views in cross-section on lines III—III, IV—IV, V—V and VI—VI of Figure 2, on an enlarged scale.

Fig. 4a is a horizontal cross-sectional view along section line 4a—4a upon Fig. 4.

Figures 7 and 8 illustrate the manner in which the ramp structure illustrated in the foregoing figures may be applied to a simple-curvature track section and to a double-curvature one, respectively.

As shown particularly in Figs. 1, 2 and 7, 8 the ramp structure comprises a number of (herein three) articulated linkage units each in the form of a deformable parallelogram, each of which comprises two profiled side-iron sections *a*, *a*; while, as shown herein each iron section *a* is in the form of an angle iron, other suitable shapes may be adopted. Each iron section such as *a* is at each end thereof, except the free end of those end iron sections at which the cars are to have access to the ramp, i. e. the right-hand end in Figs. 1 and 2, connected with a depending flange or so-called foot-plate *b* of flat circular form. The foot-plates *b* may for instance be riveted to the bottom horizontal flange or web of the angle-iron *a*, as shown at *b*¹ (see in particular Fig. 3). Each foot-plate such as *b* is mounted for restricted rotation in its own plane, in order to permit of relative angling displacements between the adjacent elements *a*, within a socket or bearing provided by a support generally designated *c*. The supports *c*, as shown in the drawings, each comprise a flat plate *c*¹, supported at a suitable vertical level above the track by means of flanged seating means *c*⁴, *c*⁴ (see in particular Figs. 4 and 5), depending from the flat plate *c*¹ and adapted to fit over the rails *r* so as to support the flat surface *c*¹ at a requisite height over the rails. As to the location of the support *c* in the ramp, this support *c*, centered upon the rail *r* by the lateral lugs *c*⁴ (Figs. 4 and 5), rests directly upon the rail (Fig. 5) or is supported thereon by a horizontal rib *c*⁵ connecting these two lugs *c*⁴ at an appropriate level (Fig. 4). The foot-plates *b* bear on the flat surfaces *c*¹ for rotation thereon. Means for retaining the plates *b* and restricting rotation thereof are provided in the form of strips or side flanges *c*², *c*², secured over the inner and outer top edges of the plate *c*¹ and having their inwardly-directed edges formed arcuately to engage portions of the periphery of the circular foot-plates *b*, and further strips or flanges *c*³, *c*³ secured over the flanges *c*², *c*² and projecting inwardly into overlapping relationship with the foot-plates *b*. The inwardly-directed edges of the said further flanges *c*³ are formed with a special configuration (clearly visible in Fig. 2) so as to restrict the relative angling movements of the iron sections *a* in a manner to be presently described.

At the points of pivotal connection between two adjacent units of the ramp structure, each support such as *c* is common to both adjacent iron sections *a* terminating at that point, and the foot-plates *b* of both angle irons *a* are so

mounted as to be rotatable in their plane within said support *c*. This rotational movement is restricted in amplitude by abutment of the vertical flanges of the angles *a* against the sloping inwardly-directed edges of the flat elements *c*³, *c*³, of the supports. The said flat elements *c*³, *c*³, are so configurated as to define a lower limit for the radius of the track-curvature in which the polygonal ramp structure may be inscribed, and this lower limit, in the exemplary embodiment shown, is somewhat less than about 4 meters. In other words, the ramp structure illustrated by way of example can be used in connection with curved track sections having a radius of curvature not less than about 4 meters.

At the points of pivotal connection between the adjacent units of the ramp structure, the supports *c* of each of the two interpivoted rows of angle irons are interconnected together through a brace or cross-bar *d*, which at each of its ends is pivoted through a pivot pin *d*¹ to the corresponding support *c*. In order that said cross-bars should insure proper seating of the supports *c* upon the rails, so as to impart to the ramp structure as a whole suitable rigidity and stability as well as for providing proper vertical alignment of the respective series of angle irons *a* with respect to the related rails, the cross-bars *d* are so constructed as to be self-adjustable in length in response to the radius of curvature assumed by the ramp structure or degree of angling between the adjacent units, at the point under consideration. To that end, each cross-bar *d* is composed of an inner tubular member *d*², on which are telescopically slidable two outer tubular parts *d*³, *d*³ mounted around the member *d*². The outer tubular parts *d*³, *d*³ are each formed with a longitudinally extending slot *d*⁵ adapted to be engaged by a corresponding pin *d*⁴, projecting from the inner tubular member *d*². Compression springs *d*¹, housed within the inner tubular member *d*² and each having an inner end thereof abutted against an intermediate web *d*⁷, provided within the member *d*² so as to divide said member into two equal compartments, are effective at all times to urge the tubular parts *d*³ outwardly and thus to press the pivots *d*¹ and also the supports *c* pivoted thereon, against the rails *r*. Sliding movement of the outer tubular parts *d*³ is restricted in amplitude by rings *d*⁸ welded thereto at their inner ends. Each of the tubular elements *d*³ comprises at its exterior end (see Fig. 4a) a boss *d*⁹ in the form of a sleeve which can pivot around the hollow spindle *d*¹. The latter is fixed upon the support *c* by a rivet *d*¹⁰ which connects this support to a horizontal plate *c*⁶. The latter is soldered to the interior lug *c*⁴ and is reinforced by a vertical rib *c*⁷ soldered to said lug *c*⁴ and to the plate *c*⁶.

At that end of the structure which connects with the tipple, i. e. the left-hand end as shown in Figs. 1 and 2, each angle iron *a* carries at its free end a circular foot-plate *b*, mounted for rotation in a support *c*, smaller in length than any of the intermediate supports *c* at which there are two adjacent angle irons *a* interconnected together. The end-supports *c*, at the free ends of the left-hand end angles *a* are interconnected by a cross-bar *e*, which is of fixed length and is assembled at its ends to two supports *c*, *c*, for example by soldering. It is maintained on the other hand at its middle for example by an anchoring teat *e*¹ (Fig. 3) to a horizontal wing *f*¹ of the frame of the tipple *f*. The ends of this cross bar *e* are curved and raised

to a suitable level to rest upon such wing f^1 of the tipple through the intermediary of the lugs e^2 .

At the opposite or right-hand end of the ramp structure, at which the cars first engage the ramp to travel up to the tipple, the free ends of the angles a are interconnected by a cross-bar d , self-adjustable in length according to the curvature of the ramp, as in the case of the intermediate cross-bars which interconnect the supports c at those points of the ramp where there are two adjacent angles a interpivoted together. In this instance, however, the end-cross-bar d is not pivoted to any supports, such as c , since no such supports are provided at this end point of the ramp. The boss or sleeve d^3 , integral with each of the outer tubular parts d^3 of the cross-bar, as previously described, can pivot about the hollow axis d^1 forming a pivot (Fig. 6) which is mounted around a rivet d^{11} connecting the horizontal lugs a^1, a^1 , secured to the respective angles a .

Moreover, at this end-point of the ramp structure, the free ends of the angles a are provided with such a shape as to insure proper engagement of the flanges of the car-wheels therewith at the time where said wheels no longer engage the rails with their rims, but start engaging the angles of the ramp with their flanges, as the cars start travelling over the ramp. This configuration is clearly shown in Figs. 1 and 2.

Figures 7 and 8 illustrate, in a more or less diagrammatical way, the manner in which the above-described articulated ramp structure may be applied to provide access of cars to a tipple f , Fig. 7 relating to a case where the ramp is provided with a simple curvature, and Fig. 8 to a case where the ramp has a double or opposite curvature therein, the radius of curvature R in each instance being about four metres.

It will be understood that the invention is in no way restricted to the specific embodiment of a ramp structure providing access to a tipple as illustrated in the drawings and described in connection therewith, and that other successful embodiments may be devised within the scope of the invention. Also, the articulated ramp of the invention is not restricted to use in connection with a tipple, but is equally applicable to other and more general cases, as for instance where it is desired to cross-connect two tracks at different levels from each other. It is accordingly desired that no restrictions be put on the scope of the invention other than the restrictions resulting from the wording of the ensuing claims.

What I claim is:

1. Ramp structure adapted to be superimposed over a haulage track section to gain a difference in level therein, which ramp structure comprises a number of parallel linkage units, each unit comprising a pair of parallel side iron sections each adapted to generally overlie a portion of a related rail of said track, supporting means each adapted to seat on one of said rails to support the adjacent ends of a consecutive pair of said iron sections over said rail at a requisite height thereabove and pivotally connecting the adjacent ends of every two iron sections of said linkage units, to allow relative angling displacements between said consecutive iron sections, and bracing means interconnecting opposite ones of said supports.

2. Ramp structure, which comprises two parallel rows of iron sections each adapted to overlie part of a related rail of a haulage track, a circular plate secured to and under each end of

each iron section, a support seating over a rail at the junction of every two iron sections of a side row thereof to present a flat top surface at a requisite level above said rail, the circular plates at adjacent ends of each two consecutive iron sections bearing on said flat surface for rotation thereon, means on said supports for retaining said plates on said supports and restricting the rotation of said plates, and means interbracing the support, located at the junction of every two iron sections of a side row thereof, with the support located at the junction of two restrictive iron sections of the opposed side row thereof.

3. Ramp structure as in claim 2, wherein said retaining and restraining means comprise arcuate flanges secured to edge portions of said flat surface to define arcs engaging peripheral portions of said circular plates, and further flanges secured over said arcuate flanges to project inwardly in overlapping relationship over said circular plates, said further flanges being formed at their inwardly directed edges with a configuration adapted to restrict the amount of angular displacement of each plate through abutment of said edges with vertical longitudinal side portions of the related iron section.

4. Ramp structure as in claim 2, wherein said interbracing means are self-adjusting and comprise an inner member and outer members telescopic over said inner member, said outer members each pivoted at its outer end to one of said supports, and spring means urging each of said outer members outwardly to press said supports against the related rails regardless of the amount of angling between the adjacent iron sections on said support.

5. In a haulage track section, a pair of rails, a tipple having a frame mounted on said rails, and a ramp structure leading up to said tipple and superimposed over said track, said ramp comprising two parallel rows of iron sections each of the latter adapted to overlie part of a related one of said rails, a circular plate secured to and under each end of each iron section, a support seating on a rail at the junction of every two iron sections of a side row thereof to present a flat top surface at a requisite level thereabove, the circular plates at adjacent ends of each two consecutive iron sections bearing on the flat surface of a support common thereto for restricted rotation thereon, and the plates at the free end of each of the two end iron sections adjacent the tipple each bearing on the flat surface of a support individual thereto, telescopic bracing means self-adjusting in length interconnecting the support, located at the junction of every two iron sections of a side row thereof, with the support located at the junction of two respective iron sections of the opposed side row thereof, and a fixed bracing means interconnecting said individual end-supports and secured to said tipple frame.

6. Ramp structure superimposed over a haulage track, which comprises two parallel rows of iron sections each of them adapted to overlie part of a related rail of said track, and including two initially parallel iron sections, a circular plate secured to and under each end of each of said iron sections other than the free end of each of said initial iron sections, supports each seating over a rail at the junction of every two iron sections of a side row thereof to present a flat top surface at a requisite level thereabove, the circular plates at adjacent ends of each two consecutive iron sections bearing on said flat surface

for restricted rotation thereon, means on said supports for retaining said plates on said supports and restricting rotation thereof, telescopic bracing means self-adjustable in length pivoted at each end to each one of each opposite pair of said supports, and a similar telescopically self-adjusting bracing means pivoted at each end to the free end of each of said initial iron sections.
